UNITED STATES PATENT OFFICE.

DON A. PHELPS, OF CINCINNATI, OHIO.

COMBINED IRONING-BOARD AND BOSOM-STRETCHER.

SPECIFICATION forming part of Letters Patent No. 425,048, dated April 8, 1890.

Application filed March 25, 1889. Serial No. 304,687. (No model.)

To all whom it may concern:

Be it known that I, DON ALANSON PHELPS, a citizen of the United States, residing at Cincinnati, in the county of Hamilton, State of Ohio, have invented certain Improvements 5 in a Combined Ironing-Board and Bosom-Stretcher, of which the following is a specification, reference being had to the accompanying drawings.

10 The object of my invention is to provide an ironing-board for ironing shirt-bosoms, which will permit of the bosom being evenly stretched before being ironed, as will more fully hereinafter appear.

15 In the accompanying drawings, Figure 1 is a perspective view of my improved ironing-board and stretcher as preferably constructed. Fig. 2 is a top view of same, with a shirt-bosom in place thereon. Fig. 3 is a side view 20 of the rear end of the board, showing the stretching mechanism in an elevated position before the bosom is stretched. Fig. 4 is a view similar to Fig. 3, showing the stretching mechanism down in position, as shown in Fig. 2, 25 with the bosom stretched.

My invention consists of a board A, of suitable size and configuration, the same having its top surface padded in the usual manner. In the front end of said board is secured the 30 spring-head, over which the collar of the shirt is secured before being stretched. This head is preferably made up of the spring-wire portion B, bent in such a manner as to form the loops b and eyes b', the two ends of said wire being suitably secured in the end of board A. A suitable covered spiral spring C is passed 35 through the eyes b' and rests in the loops b, as shown, the ends of said covered spring C being attached to the outer end portions of 40 the board A. The object in having this spiral spring covered is to prevent any rust that might otherwise accumulate on the spring from coming in contact with the collar of the shirt. If desired, a piece of rubber or other 45 elastic material may be used instead of this spiral spring.

The mechanism preferably employed for stretching the shirt-bosom is constructed as follows: A suitable roller D is pivoted between 50 the arms d, the latter being pivotally connected to the sides of the board near the rear

end thereof, and above the center of the board, as shown. To the rear end of the board A is connected the hinged piece E, the latter being of such a width as to permit of 55 its swinging between the arms d. The outer end portion of this hinged piece E is preferably beveled inward, to afford a bearing against the roller D when the bosom is stretched and locked in place, as shown in 60 Fig. 4. This hinged piece E is preferably provided with a wire or other suitable handle e on its lower face projecting out beyond its end portion to serve as a stop for the roller D, and also to assist in stretching the bosom. 65

Having described the general construction of my improved ironing-board and stretcher, I will now describe its operation. The band of the shirt is first ironed, after which it is buttoned or pinned and then slipped over the 70 spring-head, the band of the shirt bearing against the covered spiral spring C at each side, as shown. Having secured the band of the shirt over the head portion, the front flap of the shirt is passed over and around the 75 roller D, as shown, (see Figs. 3 and 4,) after which the roller D, with the flap of the shirt around it, is pressed down over the beveled face of the hinged piece E against the handle e, in which position the flap of the shirt is 80 firmly held between the beveled face of the hinged piece and the roller. This operation is accomplished while the hinged piece and the roller are elevated at an angle to the ironing-board, after which the roller and hinged 85 piece are brought down on a plane with the ironing-board, as shown in Fig. 4, the downward circular motion of said parts causing the bosom of the shirt to be evenly stretched as the flap of the shirt is caught between the 90 hinged piece and the roller for its entire width. The object of the spring-head is to permit the same to spring and give as the shirt-front is being stretched, and in this manner all danger of tearing the shirt is obviated, and at the 95 same time permitting the shirt to be thoroughly stretched.

The advantages of my improved ironing-board and bosom-stretcher are obvious. The construction is such that the shirt-front can 100 be evenly stretched without danger of tearing, which is very desirable for family use.

The construction is simple and is cheap of manufacture, and will answer all purposes of more expensive ironing-boards and stretchers. It is light and portable and can be carried 5 with ease.

While it is preferred to use the aforescribed spring-head in connection with the form of stretching device herein shown and described, the same may be used in connection with other forms of stretching devices 10 without departing from my invention.

What I claim as new, and desire to secure by Letters Patent, is—

An ironing-board having the spring-head connected to one end portion thereof and consisting of a spring-wire B, bent to form the loops b, and eyes b', and the covered spiral spring C, the latter passing through the eyes b' and resting in the loops b, in combination with a suitable stretching device connected to 15 the other end of said board, as set forth.

DON A. PHELPS.
